ALBERT H. FISHER, OF EAST CLEVELAND, OHIO, ASSIGNEE OF ONE-HALF TO DELEEBET
M. STAFFORD, OF LAKEWOOD, OHIO.

WINDOW CONSTRUCTION.

Application filed May 17, 1928. Serial No. 276,398.

This invention as indicated relates to a window construction. This application is a continuation in part of my application Serial No. 189,007, filed May 5, 1927. More particularly the invention comprises a window construction wherein the sash and frame are provided with interengaging guide members some of which may have a certain degree of transverse motion in order to compensate for irregularities in the cooperating guide members or for slight differences in the dimensions of the sash or window frame. The invention also contemplates the provision of guide members which interengage with their companion guide members so as to prevent lateral disengagement thereof and which provide for frictional engagement between the point of interlocking engagement of the companion members and one of the adjacent supports. The invention also has in view the securing of the adjustable guide member in such relation to its support that it will be free of lost motion or such amount of clearance as would tend to produce noise when such window construction is applied to various vehicles such as auto busses, street cars, and the like. It also has in view a construction adapted for a window supplied with counterweights and providing a housing for the counterbalance cable within one of the guideways. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:

Fig. 1 is a front elevation of a window construction embodying the principles of my invention; Fig. 2 is an enlarged sectional view taken along the line 2-2, shown in Fig. 1, looking in the direction of the arrows; Fig. 3 is a sectional view showing parallel window guides embodying the features of the invention; Fig. 4 is a sectional view showing a modified form of channeled guide support; Fig. 5 is a sectional view showing a pair of guide members with one of said members frictionally engaged with a support on the frame; Fig. 6 is a sectional view showing a pair of guide members with one of said members frictionally engaged with a support on the sash; Fig. 7 is a fragmentary view of a sheet metal guide member; Fig. 8 is a top view of a portion of the window sash showing the retaining plate for a grooved sheet metal guide member; Fig. 9 is a view partly in section of the upper corner of a window sash showing the retaining means for a grooved sheet metal guide member; Fig. 10 is a perspective view showing a sheet metal guide member frictionally engaged in the channelway of a support; Fig. 11 is a perspective view of a portion of a sheet metal guide member provided with a bead; Fig. 12 is a perspective view of a portion of a sheet metal guide member provided with a groove, and with its extensions in expanded position; Fig. 13 is a transverse sectional view showing a window construction with beads formed integrally upon the sash members and sheet metal guide members engaged in channelways upon the frame; Fig. 14 is a sectional view showing sheet metal guide members applied respectively to a window sash and a channeled supporting member on the frame; Fig. 15 is a fragmentary side elevation showing a portion of a grooved sheet metal guide member with anchoring means therefor; Fig. 16 is an elevation, partly in section, showing a portion of a window construction wherein a counterbalancing cable and pulley therefor is provided; Fig. 17 is a sectional view taken along the line 17-17 shown in Fig. 16, looking in the direction of the arrows; Fig. 18 is a central vertical sectional view showing a portion of a window frame with a sheet metal guide member associated therewith, and means for retaining the same in position; Fig. 19 is a view similar to Fig. 18 showing a modified form of guide member; Fig. 20 is a fragmentary view showing in enlarged detail a

tion; Fig. 4 is a sectional view showing a modified form of channeled guide support; Fig. 5 is a sectional view showing a pair of guide members with one of said members frictionally engaged with a support on the frame; Fig. 6 is a sectional view showing a pair of guide members with one of said members frictionally engaged with a support on the sash; Fig. 7 is a fragmentary view of a sheet metal guide member; Fig. 8 is a top view of a portion of the window sash showing the retaining plate for a grooved sheet metal guide member; Fig. 9 is a view partly in section of the upper corner of a window sash showing the retaining means for a grooved sheet metal guide member; Fig. 10 is a perspective view showing a sheet metal guide member frictionally engaged in the channelway of a support; Fig. 11 is a perspective view of a portion of a sheet metal guide member provided with a bead; Fig. 12 is a perspective view of a portion of a sheet metal guide member provided with a groove, and with its extensions in expanded position; Fig. 13 is a transverse sectional view showing a window construction with beads formed integrally upon the sash members and sheet metal guide members engaged in channelways upon the frame; Fig. 14 is a sectional view showing sheet metal guide members applied respectively to a window sash and a channeled supporting member on the frame; Fig. 15 is a fragmentary side elevation showing a portion of a grooved sheet metal guide member with anchoring means therefor; Fig. 16 is an elevation, partly in section, showing a portion of a window construction wherein a counterbalancing cable and pulley therefor is provided; Fig. 17 is a sectional view taken along the line 17-17 shown in Fig. 16, looking in the direction of the arrows; Fig. 18 is a central vertical sectional view showing a portion of a window frame with a sheet metal guide member associated therewith, and means for retaining the same in position; Fig. 19 is a view similar to Fig. 18 showing a modified form of guide member; Fig. 20 is a fragmentary view showing in enlarged detail a

portion of the sheet metal guide member shown in Fig. 19; Fig. 21 is a sectional view showing guide members at opposite sides of a window construction, only one of said guide members being provided with means permitting laterally slidable adjustment; and Fig. 22 is a sectional view of a window construction wherein guide members at each side of the window are provided with means permitting laterally slidable adjustment.

In the construction shown in Figs. 1 and 2, a window construction is provided wherein a window sash 1 is provided with one side member 2 having a groove 3 centrally of its vertical edge, said groove being enlarged to more than semi-circular cross-section at its inner end 4, and being adapted to receive a substantially cylindrical bead 5 provided on a guide member 6 formed of sheet metal providing a T-shaped foot or base 7 which is adapted to be received within a finishing channel strip 8, and secured to the window frame 9.

The opposite side member 10 of the sash is provided with a rectangular channel-way 11 within which is engaged a sheet metal guide member 12 providing a groove 13 having rearward extensions 14 which normally are positioned at a wide angle, as is more clearly shown in Fig. 12. Said grooved guide member is adapted to engage over a beaded guide member similar to that shown at the opposite side of the window, and illustrated in greater detail in Fig. 11. The grooved guide member is adapted to be frictionally engaged with in the channel-way and proper allowance for the spring action of the structure must be made.

In the form of construction shown in Fig. 3, a metal guide member 21 is secured to the window-frame, said guide member providing a pair of beaded guides 22 formed integrally therewith, and each positioned centrally of a channel-way 23 within which the cooperating portion of the window sash is engaged.

The window sash is not intended to frictionally engage the central parting strip 24 or the adjacent finishing flange 25 of the guide member, but is supported entirely upon the beaded guide member. The sash members 26, 27, for the upper and lower frames of the window, as illustrated in Fig. 3, are identical in shape and are provided with rectangular channels 28 in their vertical edges within which sheet metal grooved guide members 29 are engaged after the manner of those illustrated in Figs. 10 and 12. The guide member 21 attached to the frame is provided with a recess 31 to receive the cable 32 of a counter-balancing device and a pulley 33 mounted in the frame is adapted to guide the same within said recess which serves as a cable housing.

The lower end of the cable may be secured to the sash at any convenient point. The up-

per sash need not be provided with a cable inasmuch as in many constructions the upper sash is merely locked in position. The construction shown in Fig. 4 provides for the positioning of a double guide member 41 upon the window frame, said member being provided with a channel 42 and a groove 43 of more than semi-circular cross-section, and the securing of the double guide member by means of fastening members inserted centrally through apertures 44 in the parting strip 45 of the construction. With the construction of the type shown in Fig. 4, a beaded guide member attached to the sash of the window of the type shown in Fig. 6, may be utilized.

The form of construction shown in Fig. 6 relates to a single grooved member 46 attached to the frame of the window and providing a channel-way 47 to receive the adjacent portion of the sash and a groove 48 of more than semi-circular cross-section at its base, and said sash member having a groove 49 in its lateral edge within which the extensions 51 of a sheet metal guide member 52 providing a bead 53 are adapted to be received. The extensions on the sheet metal guide member are provided with alined laterally extending slots 53 through which a pin 54 is engaged to limit the degree of vertical movement of such guide member.

Instead of the guide member shown in Fig. 7 being applied to the window sash, it may be applied to a supporting member attached to the window frame, said supporting member 61 having an elongated slot 62 within which the sheet metal guide member 63 is frictionally engaged. The sash member 64 in such instance will comprise a structure providing a groove 65 at its lateral edge of more than semi-circular cross-section to engage about the bead of the guide member on the frame. The sash member shown in Fig. 5 is preferably of extruded aluminum and has a depression 66 formed on each side thereof to improve the appearance of the same to reduce the amount of material required without affecting the strength of such parts. Said side member is provided with a channel 67 opposite its grooved portion within which the window glass 68 and glazing rubber 69 is engaged.

When a sheet metal grooved member of the type shown in Figs. 10 and 12 is engaged within a channel-way at the side of a window, it is desirable to provide means for limiting the vertical movement of said member and this may be accomplished in the manner shown in Figs. 8 and 9 wherein the grooved guide member 71 is retained in position through the use of end plates 72 secured to the upper and lower faces of the side member of the sash.

In the construction shown in Fig. 13, the beaded guide members 73 are provided inte-

grally with the side members 74 of the sash and are engaged within the sheet metal grooved guide members 75 secured in channel strips 76 attached to the frame sides 77. 5 These grooved guide members may correspond in construction with that shown in Figs. 10 and 12. In place of forming the beaded guide integrally with the side of the window sash, a beaded guide 81 formed of sheet metal may be formed and firmly secured to the edge of the side member 82 of the sash, as is shown in Fig. 14. In such construction the guide member will be engaged with a grooved sheet metal guide member 83 of 15 the type shown in Figs. 10 and 12. The method of retaining such guide member within the groove in a vertical direction is illustrated in Fig. 15 wherein a pin 84 is set through the channel member and engages 20 a pair of alined notches 85 formed in the extension edges of the resilient grooved guide member.

The construction just described is adapted for combination with a cable 86 of a counter-weight, as is more clearly shown in Figs. 16 and 17. In this case the end of the cable is engaged within the sheet metal member providing a bead 87 and the groove of the other guide member 88 serves as a channel-way 25 within which the cable is housed. At the upper end 89 said grooved channel member may be cupped to prevent abrasion upon the edge of the cable. A pulley 91 is preferably supported upon a bracket 92 attached to the 30 inner side of the frame 93, said bracket providing a pair of flanges 94 between which the pivot pin 95 for the pulley is supported.

In the construction shown in Fig. 18, the grooved metal guide member 101 is secured to the window sash 102 by means of a pair of plates 103 at each end of the channel-way 104 in the respective side members, the grooved guide member terminating short of said plates with the ends of its extensions abutting the same. The plates may be formed to press against the heads of screws 105 which are set diagonally through the mortised ends of the sash and thus form a lock against the disengagement of such diagonal screws. 45

Another form of construction is illustrated in Figs. 19 and 20 wherein the grooved sheet metal guide member 106 is provided with spring metal tongues 107 secured at the respective ends of the same, which tongues are held at their free ends by suitable fastening members 108, such as screws secured to the base of the groove in the side members 109 of the sash. Apertures 111 in the grooved portions of the guide member, in alinement with the free ends of the tongues, provide for the attachment and adjustment of the screws. 50

In the construction shown in Fig. 21, a window sash 121, which may be of wood or metal, or any rigid material, has one side member 122 provided with groove 123 in its

edge having an enlarged terminal portion 124 of more than semi-circular cross-section within which a sheet metal guide member 125 having a bead is adapted to be engaged and interlocked against lateral disengagement. 55 Said sheet metal guide member is preferably secured within a channel member 126, the flanges of which serve as finishing strips. At the opposite side of the sash a similar construction is provided excepting that the side member 127 of the sash is provided with a channel-way 128 within which a sheet metal grooved guide member 129 is positioned, said guide member having resilient tongues 131 to hold the same from end-wise displacement. 60 Thus with a fixed guide member at one side and an adjustable guide member at the opposite side, a degree of lateral adjustment will be introduced into the construction sufficient to prevent a degree of friction upon the 65 guide members which would tend to lock the window and prevent its free adjustment to any desired position.

In the construction shown in Fig. 22, each side member 141 of the window sash is provided with a channel-way 142 within which a sheet metal grooved guide member 143 is engaged, said guide member cooperating with a sheet metal beaded guide member 144 secured within a finishing channel strip 145 attached to the frame. This construction has the advantage over the construction shown in Fig. 21 in that it not only compensates for irregularities in the vertical members of the window frame, but adjusts itself to slight 70 differences in the horizontal members of the window frame which may not at all times be at exactly right angles to the side members. Thus a satisfactory closing of the window may be provided for at all times through the 75 fact that the window sash is free to move on its respective guide members to a position which will squarely meet the adjacent member of the window frame.

While grooved and beaded guide members 80 formed of sheet metal have been described and illustrated in most of the forms disclosed, it is to be understood that solid or hollow guide members of metal or other suitable material may also be used. Also, instead of resilient elements being provided on the guide members, they may be provided on the channel strips which receive the guide members. 85

Other modes of applying the principle of my invention may be employed instead of the one explained, change being made as regards the mechanism herein disclosed, provided the means stated by any of the following claims or the equivalent of such stated means be employed. 90

I therefore particularly point out and distinctly claim as my invention:

1. A window construction comprising a pair of guide members supported on the frame and sash respectively, said guide mem- 95

bers having interlocking engagement with each other and means between one of said guide members and its point of support adapted to compensate for irregularities of adjustment.

2. A window construction comprising a stationary guide member and a movable guide member interlocked against lateral disengagement, one of said guide members being supported on the window sash and the other of said guide members being supported on the window frame and means provided upon one of said guide members to permit slight lateral movement thereof in relation to its supporting member.

3. A window construction comprising a stationary guide member and a movable guide member having slidable interlocking engagement with each other, one of said guide members being supported on the window sash and the other of said guide members being supported on the window frame and means provided upon one of said guide members to permit slight lateral movement thereof in relation to its supporting member.

4. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, and means frictionally engaging one of said guide members with its support to permit slight lateral movement of said guide member.

5. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, and resilient means frictionally engaging one of said guide members with its support to permit slight lateral movement of said guide member.

6. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, a channel-way provided on the support of one of said guide members,

and means frictionally engaging said guide member with said channel-way to permit of slight lateral adjustment.

7. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, a channel-way provided on the support of one of said guide members and resilient means frictionally engaging said guide member with said channel-way to permit a slight lateral adjustment.

8. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, a channel-way provided on the support of one of said guide members, means frictionally engaging said guide member with said channel-way to permit of slight lateral adjustment, and a counterbalance cable housed within said channel-way.

9. A window construction comprising a stationary guide member and a movable guide member, one of said guide members being supported on the window sash and the other of said guide members being supported on the window frame, one of said guide members providing an enlargement along its free edge and the other of said guide members providing a channel-way adapted to be engaged over and in slidable interlocking relation with said first-named member, a channel-way provided on the support of one of said guide members, means frictionally engaging said guide member with said channel-way to permit of slight lateral adjustment, a counterbalance cable housed within said channel-way, and a guide pulley associated with said channel-way and cable.

10. A window construction comprising a pair of guide members supported on the frame and sash respectively, said guide members having slidable interlocking engagement with each other, means between one of said guide members and its point of support adapted to compensate for irregularities of adjustment, and means to retain said last means from vertical displacement from its support.

11. A window construction comprising a pair of guide members supported respectively on the frame and sash, a channel-way formed in one of said supports, and one of said guide

members being formed of sheet metal providing resilient extensions adapted to frictionally engage the sides of said channel-way.

12. A window construction comprising a pair of guide members supported respectively on the frame and sash, a channel-way formed in one of said supports, one of said guide mem-

bers being formed of sheet metal providing resilient extensions adapted to frictionally engage the sides of said channel-way, and means 10 to retain said sheet metal guide member from vertical displacement from said channel-way.

Signed by me this 25th day of April, 1928.

ALBERT H. FISHER.
